UNITED STATES PATENT OFFICE.

FRANK GERGENS, OF BROOKLYN, ASSIGNOR TO ETIENNE GILLET, OF NEW YORK, N. Y.

ICE-MACHINE.

SPECIFICATION forming part of Letters Patent No. 258,927, dated May 23, 1882.

Application filed November 28, 1881. (No model.)

To all whom it may concern:

Be it known that I, FRANK GERGENS, of the city of Brooklyn, county of Kings, and State of New York, have invented a new and 5 useful Improvement in Ice-Machines, which is fully set forth in the following specification.

This invention has reference to the machines for the artificial production of cold, commonly known as "ice-machines," wherein a volatile 10 liquid or liquefiable gas is used as the refrigerating agent or refrigerant, and the cold is produced by the volatilization and expansion of the refrigerant which has been reduced to liquid form by the action of pressure aided by 15 a cooling medium. A vacuum or reduction of pressure being made above the liquid refrigerant, the latter volatilizes and expands, absorbing the heat from the surrounding material.

The present invention has reference to the 20 method and means for creating this vacuum, and for producing the pressure required for liquefaction. Heretofore there have been two modes of accomplishing this result: First, as in the machines using liquor ammoniae or so- 25 lution of ammonia in water, the vacuum has been created by the absorption or dissolution of the refrigerant (ammonia) in a material (water) for which it has great affinity, and in which the vapors are absorbed or dissolved as fast 30 as they are given off, and the pressure required for liquefaction has been produced by the ex- pulsion of the refrigerant from its absorbent or solvent by heat; secondly, as in the ma- 35 chines using methylic ether, anhydrous ammonia, sulphurous dioxide or a binary liquid of sulphurous dioxide or ammonia, and sul- phuric ether, the vacuum has been created and the pressure produced by aspiration and com- pression pumps.

40 In the present invention the vacuum is cre- ated and the pressure produced by the action of an injector. The inlet to said injector is connected with the interior of the refrigerator- or vessel wherein the refrigerant is volatilized, 45 and the outlet with the interior of the con- denser or vessel wherein it is again reduced to a liquid. The jet of gas or vapor to operate the injector is derived from heating a small portion of the liquefied refrigerant from the

condenser. The boiler is fed with this liquid 50 preferably by means of an injector independent of the first. The use of pumps is thus avoided without requiring from the refrigerant any solvent or carrier, such as the water in the liquor-ammonia machine, and consequently 55 without requiring any absorber wherein the absorption may take place.

The difficulties due to the use of pumps in connection with the corroding agents commonly employed as refrigerants, as well as those en- 60 countered with the liquor-ammonia machine, or machines working on the same principle, are too well known to require mention. By the present invention they are entirely or to a great extent overcome. Moreover, the expense 65 of the pumps, the noise attending their operation, as well as the care, constant watchfulness, and labor necessitated in their super- 70 vision, are done away with. The apparatus needed is reduced to its simplest, most com- pact, economical, and durable form.

In order that the invention may be fully understood, an ice-machine constructed in ac- cordance therewith is represented in the ac- 75 companying drawing, which forms a part of this specification. A view in vertical section and elevation is shown.

A is the refrigerator; B, the condenser; C, the boiler, and D E the two injectors. These apparatus may be of any ordinary or suitable 80 construction. As shown, the refrigerator A consists of a horizontal vessel, *a*, with numer- 85 ous tubes extending from end to end, and a tank, *b*, which contains a non-congealable li- quid having free circulation through the tubes, of the aforesaid vessel *a*, and in which also are placed cans *c* for holding the water to be frozen. The condenser consists of a horizontal vessel divided into three compartments, *d e f*, and provided with a system of tubes extending 90 through the intermediate compartment, *e*, and connecting the end compartments with each other; and the boiler is an upright tubular one of an ordinary type. The refrigerator is pro- 95 vided with a vacuum-gage, F, and the boiler and condenser with pressure-gages G H, and the boiler also with the level-indicator I.

The interior of the vessel *a* is connected at

the top with the inlet of the injector D by a pipe, *g*, provided with regulating-cock, and at the bottom with the lower part of the compartment *e* of the condenser by a pipe, *h*, also provided with a suitable cock. The outlet of the injector D is connected by the pipe *i* with the upper part of the condenser. The injector D is also connected with the upper part of the central chamber, *k*, of the boiler C by a pipe, *l*, provided with a suitable cock, through which pipe the jet or gas under pressure is supplied to operate the said injector.

From the pipe *h* a branch pipe, *m*, leads to the boiler C, and in this pipe the injector E is placed. It is supplied by the branch *n* from the pipe *l*, and feeds a small portion of the liquid refrigerant from the condenser into the boiler to supply the evaporation.

As shown, the boiler is heated by steam, *p* being the inlet and *q* the outlet or drip pipe, whence the steam escapes in a condensed state. Any other suitable means of heating the refrigerant in the boiler to generate the required pressure could be used.

The condenser is kept cool by a circulation of water or other cooling medium, *r* being the inlet, and *s* the outlet.

In operation the refrigerant is volatilized by reduction of pressure in the vessel *a*, lowering the temperature of the surrounding non-condensable liquid, which, circulating around the cans, lowers their temperature and freezes the water in them. The volatilized refrigerant ascends the pipe *g* to the injector D, wherein it meets the jet from the boiler C, and with the material of said jet passes into the compartment *e* of the condenser B, where, under the influence of the pressure due to the jet and the cooling action of the water or other circulating medium, it is reduced to a liquid. From the condenser the main portion of the refrigerant flows through the pipe *h* into the vessel *a* of the refrigerator A, to be again volatilized, while a small portion passes through the branch *m*, and is fed by the injector E into the boiler C.

The circulation of the refrigerant as well between the boiler and injectors as between the injectors, condenser, and refrigerator is regulated by the cocks, as is also the circulation of the cooling medium in the condenser and of the heating medium in the boiler.

The apparatus shown is adapted to the use of a simple refrigerant or of a compound (binary) liquid, in which both component parts are volatile—such as the ethero-sulphurous dioxide described in Letters Patent No. 224,246, granted to Du Motay and Rossi February 3, 1880.

If it is desired to use a binary liquid wherein one component is non-volatile, as described in Letters Patent No. 236,843, Rossi and Beckwith, January 18, 1881, means must be used to insure the circulation of the non-volatile component between the condenser, refrigerator, and boiler. In using these binary liquids

the volatile—or when both are volatile the more volatile—component is absorbed in the other; but the latter acts altogether different from the water in the liquor-ammonia machines. It assists in the liquefaction of said volatile or more volatile component preparatory to its revolatilization in the refrigerator, instead of serving to carry the refrigerant into the boiler, to be thence expelled and compressed in the condenser, and the absorption takes place in the condenser itself, instead of requiring an independent absorber with the boiler between. It is obvious, however, that in using binary liquids of the kinds indicated under this invention the non-volatile or less volatile component would perform both roles, the condenser having a double operation—to wit, as a condenser to the refrigerator and an absorber to the boiler. It is obvious, also, that the vessel could be divided and one part used as a condenser to the refrigerator and the other as an absorber or condenser to the boiler, and that other modifications could be made.

An injector supplied with a jet from the boiler could be placed between the refrigerator and absorber of a liquor-ammonia machine, or machine operating on the same principle, in order to assist in creating a vacuum in the refrigerator, and thereby effecting the volatilization of the liquefied refrigerant, and in order also to produce pressure in the absorber, thereby aiding in producing the liquefaction by absorption of the volatilized refrigerant. It could also be used in machines operated by compressed air, or by other gas which is simply condensed, not liquefied, in the machine, and which produces cold by simple expansion, instead of volatilization and expansion; but the same advantages would not accrue as in machines wherein the refrigerant is alternately liquefied and volatilized.

A number of injectors arranged to supplement the action one of another could be used, instead of a single one, if desired.

It may be here observed that heretofore an injector apparatus has been connected with a refrigerator in which anhydrous ammonia is volatilized, a vessel containing water, and a receptacle for the liquor ammonia made by the absorption of the ammonia in water; but this injector apparatus has a very different function from the injector D in the present invention, and the machine as a whole is essentially unlike that herein described. The inlet of the injector apparatus is connected with the water-vessel instead of with the refrigerator, and the nozzle or jet opening with the refrigerator instead of with a reservoir of fluid under pressure, such as the boiler C. The injector in the old machine is, therefore, simply a mixing or absorbing device, the energy of the expanding ammonia serving to draw the water from its vessel and force it as liquor ammonia into its receptacle, whereas in the present invention the energy to operate the machine is de-

rived from the pressure of fluid in the boiler, which is greater than that of the expanding refrigerant in the refrigerator, and draws off the latter, thus producing an exhaustion in the refrigerator and a compression in the condenser by the action of the jet of fluid under pressure.

It is obvious that a feed-pump could be used to supply the liquid or liquefied refrigerant to the boiler, if desired.

Having now fully described my said invention and the manner of carrying the same into effect, what I claim is—

1. The improvement in the artificial production of cold, consisting in aiding or effecting the volatilization or expansion of the liquefied or condensed refrigerant by making a vacuum or reduction of pressure above it through the action of a jet in an injector, substantially as described.

2. The improvement consisting in aiding or effecting the alternate volatilization or expansion and liquefaction or condensation of the refrigerant through the action of an injector, substantially as described.

3. The improvement consisting in creating, by means of an injector, a vacuum above the liquefied or condensed refrigerant in the refrigerator, in producing, also, by means of an injector, pressure upon the volatilized or expanded refrigerant in the condenser of an ice-machine, and in conducting the liquefied or condensed refrigerant from said condenser to said refrigerator, the volatilization or expansion, liquefaction or condensation, and return of the refrigerant being effected successively and continuously, substantially as described.

4. In an ice-machine operating by the alternate volatilization and liquefaction of the refrigerant, the improvement consisting in aiding or effecting the liquefaction of the said refrigerant by a jet acting through an injector, substantially as described.

5. The improvement in the artificial production of cold, consisting in heating a portion of the liquefied or condensed refrigerant so as to bring the same under pressure, supplying a jet of said refrigerant to an injector, and thereby aiding or effecting the volatilization or expansion of the liquefied or condensed refrigerant, and also the liquefaction or condensation of the volatilized or expanded refrigerant, or either of said operations of volatilization and liquefaction, substantially as described.

55 6. The improvement in ice-machines consisting in heating in a boiler a liquefied or condensed refrigerant to bring the same under pressure, supplying a jet of said heated material to an injector, so as to create a vacuum in

the refrigerator, and thus to volatilize or expand the liquid or condensed refrigerant therein, forcing the volatilized or expanded refrigerant by the action of said jet, together with the material composing the latter, into a condenser, wherein the refrigerant is liquefied or condensed by the pressure, aided by a cooling medium, and supplying the liquefied or condensed material to said refrigerator and to said boiler, substantially as described.

7. The combination of the refrigerator, injector, and boiler, the injector having its inlet connected with said refrigerator and being supplied from said boiler, substantially as described.

8. The combination of the refrigerator, injector, boiler, and condenser, the said injector having its inlet connected with the refrigerator and its outlet with the condenser, substantially as described.

9. The combination, with the refrigerator of an ice-machine, of an injector having its inlet connected with said refrigerator, and means, as indicated, for supplying a jet to said injector, so as to produce a vacuum or reduction of pressure in said refrigerator, substantially as described.

10. The combination, with the condenser of an ice-machine, of an injector having its outlet connected with said condenser, and means, as indicated, for supplying a jet to said injector, so as to force the refrigerant into said condenser, substantially as described.

11. The combination, with the refrigerator and condenser of an ice-machine, of an injector having its inlet connected with the refrigerator and its outlet with the condenser, and means for supplying a jet to said injector, so as to withdraw the refrigerant from the refrigerator and force it into said condenser, substantially as described.

12. The combination of the refrigerator, injector, condenser, and return-pipes, substantially as described.

13. The combination of the boiler, refrigerator, injector, condenser, and return-pipes, substantially as described.

14. The combination of the boiler, refrigerator, injector, condenser, return-pipes, and contrivance connected with the return-pipe to the boiler, substantially as described.

In testimony whereof I have signed this specification in the presence of two subscribing witnesses.
